COMBINED CLOSURE CAP AND DISPENSER FOR
COLLAPSIBLE TUBES

Warren M. Mansfield, Glendale, Calif., assignor to
John F. Donahoo, Los Angeles, Calif.

Application October 18, 1954, Serial No. 32,707

Term of patent 14 years

(Cl. D58—26)

FIG. 1.

FIG. 2.

FIG. 3.

FIG. 4.

FIG. 5.

Fig. 1 is a side elevational view of a combined closure cap and dispenser for collapsible tubes, showing my new design;

Fig. 2 is an elevational view looking at the right side of Fig. 1;

Fig. 3 is a top plan view thereof;

Fig. 4 is a top plan view thereof showing the dispenser portion in open position;

Fig. 5 is a bottom plan view thereof showing the dispenser portion in closed position.

I claim:

The ornamental design for a combined closure cap and dispenser for collapsible tubes, substantially as shown.
